UNITED STATES PATENT OFFICE.

ARTHUR R. McARTHUR, OF GARY, INDIANA, ASSIGNOR TO AMERICAN SHEET AND TIN PLATE COMPANY, OF PITTSBURGH, PENNSYLVANIA, A CORPORATION OF NEW JERSEY.

DOUBLING APPARATUS.

Application filed January 14, 1928. Serial No. 246,878.

This invention relates to doubling apparatus of the roll type used for doubling sheets or plates in the manufacture of light gage sheets or plates, and has for its object the provision of automatic means for packing the doubled sheets or plates in edgewise position on a wheeled carriage.

The present invention relates particularly to that class of automatic packing means for the sheets or plates disclosed in my Patent No. 1,688,982, granted September 11, 1928, and differs therefrom in the provision of an improved and novel operating means for the packing head.

15 In the drawings—

Fig. 1 is an end view of the apparatus, the upper portion of the housings and doubler mechanism being omitted since it is standard mechanism and forms no part of this invention; and

Fig. 2 is a sectional elevation taken on the line II—II of Fig. 1.

Referring more particularly to the drawings, the numerals 2 and 3 designate the 25 doubler side housings which are spaced apart and which are connected together by transverse members 4 and 5 and by other structural members adjacent their upper ends (not shown).

30 The sheets or plates to be doubled are passed between the housings 2 and 3 and are adapted to be forced down between a pair of doubling rolls 6 and 7 by the doubling knife 8.

35 A pair of guide plates 9 and 10 are arranged transversely between the housings 2 and 3 and are adapted to receive the doubled sheets or plates and guide them downwardly onto a wheel carrier or truck A located in 40 a passageway B between the lower portions of the side housings 2 and 3.

The truck A comprises a flat chassis or body 12, axles 13, and flanged wheels 14. A hand-brake mechanism is provided to frictionally engage the one pair of wheels so as to normally resist free movement of the truck, and comprises a brake-shaft 15 journaled on the chassis 12 and provided with a hand operating lever 16 having a ratchet lock 17. A pair of brake shoes 18 are carried by the shaft 15 and adapted to engage the truck wheels.

A sheet or plate stop head 20 is secured to the truck chassis 12 adjacent one end and ex-

tends upwardly therefrom, and is adapted to 55 support the doubled sheets or plates in edgewise position as they are delivered onto the truck.

A packing mechanism is provided for packing the sheets or plates forwardly toward the stop head 20, and comprises a head member 21 keyed on a shaft 22 journaled in bearings 23 on the doubler side housings 2 and 3.

The head 21 is inclined rearwardly above 65 and below a point intermediate its ends. The upper inclined portion is of greater length than the lower portion and is adapted to form a guide for guiding the doubled sheets and below a point intermediate its ends. The upper inclined portion is of greater length than the lower portion and is adapted to 70 form a guide for guiding the doubled sheets into position on the truck A, while the lower inclined portion forms the packing portion and is inclined at substantially the same angle as the stop head 20, so as to bear equally against the sheets which are packed against said stop head.

75 The doubling knife 8 is adapted to be operated by a crank-shaft 25 journaled on the doubler housings and having its crank portions 26 connected to the knife by connecting rods 27. A disk 28 is secured to one 80 end of the shaft 25 and has a pin 29 eccentrically mounted therein and projecting therefrom. The pin 29 is positioned opposite to the cranks 26 of the shaft 25 so that when said cranks are in their upper position, 85 the pin 29 will be in its lowermost position.

A lever 30 has one end keyed to the shaft 22 and has its other end connected to the eccentric pin 29 by a link 31. Therefore, the lever 30 will be raised and lowered upon each 90 revolution of the shaft 25 and disk 28 so as to rock the shaft 22 and packing head 21 back and forth, or away from and toward the piled sheets.

When the cranks 26 are in their upper position the knife 8 will be raised and the pin 29 will be in its lower position which will move the packing head 21 against the piled sheets. When the cranks are rotated to their lower position to cause the knife 8 to force 100 the sheets between the rolls 6 and 7, the pin 29 will be moved to its upper position so as to raise the lever 30 and rock the packing head 21 rearwardly to permit the doubled sheets to fall between the head 21 and the pile 105 of sheets on the truck A.

The crank-shaft 25 and doubling rolls 6 and 7 will be operated by an electric motor

and gearing such as is common in the well-known form of standard doubler.

In operation, the carriage or truck A is backed into the passageway B between the 5 housing sides 2 and 3 until the head 20 is close to or in contact with the packing head 21, and the brakes 18 are set to hold the truck against free movement from this position, but will yield frictionally to allow the truck 10 to move when force is applied thereto.

The doubler mechanism is then set in motion and as a sheet or plate is doubled and forced between or through the rolls 6 and 7, which rolls being spring-pressed against the 15 sheet tend to complete the doubling and press the sides of the sheet closely together, while the packing head 21 will be rocked backwardly to permit the doubled sheet to fall into position on the truck A.

20 As the doubler knife 8 is elevated in readiness to permit another sheet to be doubled, the packing head will be rocked forwardly to pack the sheets and force the truck A forward an amount equal to the thickness of the 25 doubled sheet.

While I have shown and described one specific embodiment of my invention it will be understood that I do not wish to be limited thereto, since various modifications may be 30 made without departing from the scope of my invention as defined in the appended claims.

I claim—

1. A doubling apparatus for sheets and plates comprising, in combination, a housing 35 having a passageway through its lower end through which a wheeled carrier is adapted to pass, a wheeled carrier adapted to be located in said passageway, said carrier being provided with an upright head at one end to support the doubled sheets or plates delivered onto said carrier, a doubling mechanism 40 mounted on said housing, said mechanism including a doubling knife and doubling rolls, and means including a crank-shaft for operating said doubling mechanism, means for receiving and guiding the 45 doubled sheets or plates onto said carrier, a packing head supported on said housing and adapted to be rocked back and forth to pack 50 the doubled sheets on said carrier, said head having a constant stroke and being adapted to move said carrier forwardly a distance substantially equal to the thickness of the 55 doubled sheets or plates so as to position said carrier to receive the next doubled sheet or plate, and means operable by said crank-shaft for rocking said packing head.

2. A doubling apparatus for sheets and plates comprising, in combination, a housing, 60 a doubling mechanism mounted on said hous-

ing, said mechanism including a doubling knife and doubling rolls, and means including a crank-shaft for operating said doubling mechanism, a shaft journaled on said housing, a packing head secured on said shaft, said head being adapted to be rocked back and forth to pack the doubled sheets, a lever secured to said last-named shaft, a pin mounted eccentrically on said crank-shaft, 65 and a link connecting said pin and said lever so that said lever will be rocked by each revolution of said crank-shaft.

3. A doubling apparatus for sheets and plates comprising, in combination, a housing, 70 a doubling mechanism mounted on said housing, said mechanism including a doubling knife and doubling rolls, a crank-shaft, connecting rods connecting the cranks of said shaft to said knife for operating said knife, a shaft journaled on said housing, a packing head secured on said shaft, said head being adapted to be rocked back and forth to pack the doubled sheets, a lever secured to said last-named shaft, a pin mounted eccentrically on said crank-shaft, 75 and a link connecting said pin and said lever so that said lever will be rocked by each revolution of said crank-shaft, said pin being positioned opposite to said cranks relative to the longitudinal axis of said crank-shaft.

4. A doubling apparatus for sheets and plates comprising, in combination, a housing 80 having a passageway through its lower end through which a wheeled carrier is adapted to pass, a wheeled carrier adapted to be located in said passageway, said carrier being provided with an upright head at one end to support the doubled sheets or plates delivered onto said carrier, a doubling mechanism 85 mounted on said housing, said mechanism including a doubling knife and doubling rolls, and means including a crank-shaft for operating said doubling mechanism, connecting rods connecting the cranks of said shaft to said knife, a shaft extending transversely of 90 said passageway and journaled in bearings on said housing, a packing head secured on said last-named shaft and adapted to be rocked back and forth to pack said sheets on said carrier, a lever secured to said last-named shaft, a pin mounted eccentrically on said crank-shaft, 95 and a link connecting said pin and said lever so that said lever will be rocked by each revolution of said crank-shaft, said pin being positioned opposite to said cranks relative to the longitudinal axis of said crank-shaft.

In testimony whereof, I have hereunto set my hand.

ARTHUR R. McARTHUR.
